UNITED STATES PATENT OFFICE.

REYNOLDS C. FRAMPTON, OF PITTSBURG, PENNSYLVANIA, ASSIGNOR TO PITTSBURG
WATER HEATER COMPANY, OF PITTSBURG, PENNSYLVANIA, A CORPORATION OF
NEW JERSEY.

HEATER.

961,434.

Specification of Letters Patent. Patented June 14, 1910.

Application filed October 12, 1908. Serial No. 457,384.

To all whom it may concern:

Be it known that I, REYNOLDS C. FRAMPTON, a citizen of the United States, residing at Pittsburgh, in the county of Allegheny and State of Pennsylvania, have invented certain new and useful Improvements in Heaters, of which the following is a specification.

The invention relates to heaters and particularly to hot water heaters for use in house heating systems, and has for its primary objects; the provision of a simplified and efficient heater which may be used with either gas or solid fuel without any change or alteration of the parts whatever; the provision of a heater of the character specified wherein radiation from the heater casing is reduced to a minimum; and the provision of a heater wherein both solid and gaseous fuel may be used efficiently together and the temperature of the water automatically and positively regulated. One embodiment of the invention is illustrated in the accompanying drawing, wherein:—

The figure is a longitudinal section through the heater.

Heretofore heaters capable of using both gas and solid fuel, such as coal or wood, have been constructed, but the constructions have been such that considerable alteration was necessary in order to change from one form of fuel to the other, such as the removal of the gas burners to permit coal to be used, and the removal of the coal grate to permit the installation of the gas burners. This changing is a matter of inconvenience and difficulty, and my invention is intended to obviate the difficulty by the provision of a construction in which the combustion chambers for gas and solid fuel are entirely independent and separate, so that the grates and burners may be left permanently in position, and either solid fuel or gas may be burned without the necessity of removing the parts not in use. Another objection to the majority of the old arrangements wherein the fuel was interchangeable, arose from the fact that where a single combustion chamber was used, its shape and construction could not be made to suit perfectly both forms of fuel, and an inefficient operation with one of the fuels resulted. My invention is designed to overcome this difficulty, as the combustion chambers for the fuel are entirely independent and may be both constructed to suit the fuel employed.

Referring first to the general arrangement shown in the drawing, 1 is the casing of the heater provided at its upper end with the outlet flue 2; 3, 4, 5 and 6 are vertical coils preferably of copper which communicate at 60 their upper ends with a transverse pipe 7, and at their lower ends with a transverse pipe 8, such transverse pipes being located outside of the heating casing; 9 is a pipe connecting the right hand end of the transverse pipes; 10 is the outlet pipe leading to the radiators; 11 is the return pipe from the radiators; 12 is the combustion chamber for the solid fuel, which chamber is provided with a grate 13 beneath which is the 70 ash pit 14; 15 is the gas combustion chamber provided at its lower end with a set of burners 16 fed from the gas pipe 17; 18 and 19 are water containing walls, 20 is the pipe leading from the upper portion of the water 75 containing wall 18 to the left hand end of the transverse pipe 7; 21 is a pipe leading from the lower end of the return pipe 7 to the lower portion of the water containing wall 18; 22 is a thermostat rod carried by a 80 copper tube extending into the transverse pipe 7 whereby the flow of gas through the pipe 7 is automatically controlled; and 23 is a manually operable valve for controlling the flow of gas through the pipe 7. 85

The thermostat rod 22 operates the valve disk 24 through the medium of the coöperating levers 25 and 26. The particular kind of thermostat employed is immaterial as far as the present invention is concerned, and 90 will therefore not be described in detail. A pilot light 27 is preferably employed, and this pilot light is supplied by means of the pipe 28 which connects with the gas pipe above the valve 23. The water containing walls 18 and 19 are connected together by means of the passages 29, 30, 31, 32, 33, 34 and 35, so that an effective circulation may be had. The gas combustion chamber 15 located intermediate the water containing 100 walls 18 and 19 opens at its upper end into the casing just beneath the coils 3, 4, 5 and 6, and the heat not absorbed by the water containing walls passes up about the copper coils, the products of combustion passing 105 through the flue 2.

In operation the water heated in the water containing walls 18 and 19 passes up through the pipe 20 to the transverse pipe 7 and thence out through the outlet pipe 10. 110

The water heated in coils 3, 4, 5 and 6 passes upward therethrough and out into the transverse pipe 7 and thence through the outlet pipe 10. On the return through the 5 pipe 11, part of the water passes down through the pipe 21 to the lower portion of the walls 18 and 19, while another portion of the water is diverted laterally into the transverse pipe 8 from which it passes into 10 the coils. It will be seen from the foregoing that a proper circulation is provided for throughout the heater.

The advantages of the construction will be readily apparent. Solid fuel may be 15 burned upon the grate 13 without in any way interfering with the operation of the burners 16, and the burners 16 may be operated without interfering with the use of solid fuel upon the grate 13. The two kinds 20 of fuel may be used separately or if desired, both fuels may be used at the same time. The latter method of operation is advantageous when it is desired to heat the water very rapidly, or in case the gas pressure is 25 low and insufficient to provide the requisite amount of heat. It will be noted that by making the two combustion chambers entirely independent there is no necessity of any alteration or rearrangement of the parts 30 when it is desired to change from one fuel to another, and that the shape of the chambers is such that an efficient operation is insured when either class of fuel is employed. The use of the water containing walls 18 35 and 19 reduces the amount of radiation from the casing to a minimum, does away with the necessity of using fire-brick, and obviates any danger of the casing burning out. The thermostat is of great value at times 40 when both coal and gas are used at the same time. Under these conditions no damage will be done in case the solid fuel fire burns out or goes out, as the thermostat will operate the controlling valve to admit more and 45 more gas as the fire on the grate burns down, and the water in the system is maintained at a uniform temperature regardless of the condition of the fire upon the grate. Other advantages incident to the construction will 50 be apparent to those skilled in the art.

Having thus described my invention and illustrated its use, what I claim as new and desire to secure by Letters Patent is the following:—

- 55 1. In combination in a water heater, a container for water to be heated, and two independent combustion chambers arranged in telescopic relation with an interposed water containing wall in communication 60 with the container, the chambers being positioned so as to supply heat to the container and the inner chamber being provided with a grate for solid fuel and the outer one with gas heating means.

- 65 2. In combination in a water heater, a

container for water to be heated, and two independent combustion chambers arranged in telescopic relation with an interposed water containing wall, and a second water containing wall outside the outer chamber both in communication with the container, the chambers being positioned so as to supply heat to the container and the inner chamber being provided with a grate for solid fuel and the outer one with gas heating means.

3. In combination in a water heater, a container for water to be heated, two independent combustion chambers, one of which is provided with a gas burner, and the other 80 of which is provided with a grate for burning solid fuel, and thermostatic means governed by the temperature of the water heated for controlling the flow of gas to the burner.

4. In combination in a water heater, a container for water to be heated in its upper portion, a combustion chamber therebeneath provided with a grate for burning solid fuel, a wall inclosing the wall of the combustion 90 chamber spaced away therefrom, a gas burner for supplying heat to the space between the walls, the said space being open to the container.

5. In combination, a casing provided with 95 a coil tube container for water to be heated in its upper portion and having a base consisting of a pair of walls one inside the other with a space between open at its upper end to the interior of the casing, a 100 burner at the lower end of said space, and a grate inside the inner wall.

6. In combination in a water heater, a container for water to be heated, two independent and separate combustion chambers 105 one inside the other, a pair of walls with a space between communicating with the container and constituting the dividing member between the chambers, a second pair of spaced walls communicating with the container and constituting the outside wall of 110 the outer chamber, a grate for the inner chamber, and gas heating means for the outer chamber.

7. In combination in a water heater, a 115 casing provided with a set of coils, a combustion chamber beneath the coils having for its sides a pair of walls with a space between communicating with the coils, a surrounding wall spaced away from the pair 120 of walls with the interposed space open to the interior of the casing, gas heating means for said interposed space and a grate for the combustion chamber.

8. In combination in a water heater, a 125 casing provided with a set of coils, a combustion chamber beneath the coils having for its sides a pair of walls with a space between communicating with the coils, a surrounding member spaced away from the 130

pair of walls with the interposed space open to the interior of the casing and comprising a pair of walls with the space between communicating with the coils, gas heating means for the said interposed space, and a grate for the combustion chamber.

9. In combination in a water heater, a casing provided with a set of coils, a combustion chamber for solid fuel beneath the 10 coils and having a water containing wall, a second water containing wall surrounding

the first wall and spaced away therefrom, and gas heating means for the space between the walls, such space communicating at its upper portion with the interior of the casing. 15

In testimony whereof I have hereunto signed my name in the presence of the two subscribed witnesses.
